UNITED STATES PATENT OFFICE.

JAMES H. RODEN, OF TORONTO, ONTARIO, CANADA.

ELECTRIC GAS IGNITER.

Application filed September 8, 1923. Serial No. 661,691.

To all whom it may concern:

Be it known that I, JAMES H. RODEN, of the city of Toronto, in the county of York, Province of Ontario, Canada, a subject of 5 the King of Great Britain, have invented certain new and useful Improvements in Electric Gas Igniters, of which the following is a specification.

This invention relates to gas igniters and 10 more particularly to the type adapted for household or factory use in which the igniter is connected to the lamp circuit therein and is used to light gas or fuel vapor appliances and my objects are to so construct 15 the igniter that it will be absolutely safe in use and to provide a device which is simple in design and of few and readily assembled parts.

I attain my object by means of the constructions hereinafter described and illustrated in the accompanying drawings in which—

Fig. 1 is a plan view of my improved device;

Fig. 2 a longitudinal cross section thereof on the line 2—2;

Fig. 3 a cross section of the same, on the line 3—3 in Fig. 2;

Fig. 4 a cross section of the same, on 30 the line 4—4 in Fig. 2; and

Fig. 5 a horizontal sectional detail on the line 5—5 in Fig. 2.

1 is a casing of insulating material which is divided longitudinally to form two parts. 35 Each part is formed with bosses 2 having holes therethrough for the passage of the bolts 3 whereby the parts of the casing are held together. These bosses are arranged transversely of the casing and extend substantially to the line of division so that no portions of the bolts are exposed within the casing. In the casing is suitably carried the transformer 4 which is of ordinary construction and includes primary and 45 secondary windings (not shown).

Each part of the casing is formed with an integral socket 5 and in these sockets is supported the base plate 6 of an ordinary switch including a push button 7 having 50 an enlargement 8 formed on its lower end.

The button is guided in an opening 9 formed in each part of the casing and the enlargement 8 is adapted to engage the wall of the casing to prevent the button being 55 withdrawn through the opening 9. This enlargement is also adapted to engage the

upper surface of the ribs 10 of the socket 5 whereby the downward push of the button is limited to prevent damage to the switch.

The transformer primary winding is connected by means of the circuit 11 through the medium of the switch 6 to a suitable source of electrical supply. The small low tension current induced in the secondary winding is used to heat a small resistance coil 12 which is carried by a metal tube 13 supported in the casing 1 as follows. The casing is provided with a boss 14 through which an opening 15 is formed 60 which is adapted to receive the tube 13. The division of the casing is formed through the boss and opening so that one half of each of them is formed in each part of the casing whereby the tube may be gripped or clamped between the casing parts when they are in juxtaposition. To prevent the withdrawal of the tube through the opening 15 I form laterally extending lugs 16 on the tube, each lug adapted to engage a recess 17 65 formed in the wall of each portion of the opening 15. These lugs also prevent the tube turning relative to the casing. An insulating bushing 18 is fitted in the end of the tube 13 that is remote from the casing 1. This bushing is preferably held in place by displacing the metal of the tube to form an angular groove 19 and a shoulder 20, the latter being adapted to engage the inner end of the bushing. The outer 70 end of the tube is also suitably displaced to form shoulders 21 adapted to engage the outer end of the bushing.

To a conductor 22 having an integral tang 23 adapted to be passed through an opening in the bushing 18, is connected, by means of a screw, one end of the resistance coil 12. The other end of this coil is connected, by means of a screw 24, to a perforated metal cap 25. This cap is fitted on the outer end of the tube 13 and secured thereon by pressing the inner end of the cap into the groove 19 formed in the periphery of the tube. It will be noted that the outer end of the coil 12 is passed through one of the 80 perforations in the cap 25 and then secured under the head of the screw 24 to facilitate the assembly of the device.

The secondary winding of the transformer is connected, by means of a wire 26, with the tang 23 and the secondary circuit is completed by a wire 26^a connecting

the tube 18 with the second terminal of the secondary winding. To enable the latter connection to be easily made the tube is formed with an integral projection 27, extending within the casing, the wire 26^a being soldered to this projection.

The device is used by connecting the wires of the circuit 11 to the household wiring which causes the current therein to flow through the primary winding of the transformer 4 when the switch button 7 is pushed down to close the switch 6. The induced current then flows from one terminal of the transformer secondary winding, through the wire 26, tang 23, conductor 22, coil 12, cap 25, tube 13, projection 27, wire 26^a to the second terminal of the secondary winding thereby heating up the resistance coil 12 which is adapted to ignite the gas pouring out through the burner outlet openings in a gas appliance.

What I claim is:

1. An electric gas igniter including an igniting element, a divided casing adapted to carry the igniting element between the parts thereof and shaped to form a receptacle and a switch socket, the latter being separate from the receptacle, the division of the casing being through the socket and the receptacle; and a switch connected in a supply circuit for opening and closing said circuit, the switch being carried in the said socket. 90

2. An electric gas igniter including a casing having an opening formed therein, the casing being divided through the opening to form two parts; and a tube adapted to be received in said opening and carrying a heating element, the parts of the casing and tube being adapted to engage one another to prevent withdrawal of the tube while the parts of the casing are in juxtaposition.

3. An electric gas igniter including a heating element, a casing having an opening formed therein, the casing being formed in two parts, the division being through the said opening, each part being provided with a lateral recess communicating with the said opening; and a tube extending from the casing for carrying the said element and adapted to be received within the said opening and provided with lateral projections adapted to be received in the said recesses.

4. An electric gas igniter including a heating element, a casing having an opening formed therein, the casing being formed in two parts, the division being through the opening, each part being provided with a lateral recess communicating with the said opening; and a tube extending from the casing for carrying the said element and adapted to be received within the said opening and provided with laterally extending

integral lugs adapted to be received in the said recesses.

5. An electric gas igniter including an igniting element; a divided casing adapted to carry the igniting element between the parts thereof and shaped to form a receptacle, a switch socket and a guide for a push button, the socket being separate from the receptacle, the division of the casing being through the socket, guide and receptacle; a switch connected in a supply circuit, the switch being carried in the said socket portions; and a push button adapted to actuate the switch and mounted in the said guide portions. 90

6. An electric gas igniter including a casing having an opening formed therein, the casing being divided through the opening to form two parts; and a tube adapted to be received in said opening and carrying a heating element, the parts of the casing and tube being adapted to engage one another to prevent the turning of the tube relative to the casing while the parts thereof are in juxtaposition. 90

7. In an electric gas igniter, a casing of insulating material formed in two parts, each part having a boss formed therein extending substantially to the line of division of the casing; and means passing through the said boss for securing the parts of the casing together. 95

8. In an electric gas igniter, a casing of insulating material divided longitudinally to form two parts, each part having transversely arranged bosses formed therein extending substantially to the line of division of the casing; and bolts passing through the said bosses for securing the parts of the casing together. 100

9. In an electric gas igniter, a divided casing; and a tube carried by and extending from the said casing for carrying a heating element having one end electrically connected to the tube, the tube having an integral projection adapted to extend within the casing to form an electric connection. 105

10. In an electric gas igniter, a casing of insulating material; a metal tube carried by and extending from the casing and forming part of the igniter circuit and having an insulating bushing carried at its outer end; a perforated cap secured to the tube; a connector also forming part of the igniter circuit and provided with a tang passed through the said bushing; a heating element electrically connected to the connector and to the said cap. 115

11. An electric gas igniter constructed as set forth in claim 10 in which the tube is formed with an annular displacement to provide a groove and a shoulder, the latter being adapted to engage the bushing, the inner end of the cap being adapted to be pressed into the said groove. 125

12. In an electric gas igniter including a casing having an opening therein, the casing being divided through the opening to form two parts, each part having a portion of a 5 socket, including an upper rib, formed integrally therein; a normally open switch including a base plate adapted to be received in the said socket and connected in a supply circuit; and a push button for closing the 10 switch adapted to be received in the opening and having an enlarged end adapted to prevent the withdrawal of the button when the parts of the casing are in juxtaposition, the enlarged end being adapted to engage the 15 ribs to prevent damage to the switch when the button is depressed.
13. In an electric gas igniter, a casing formed of insulating material and in two parts adapted to enclose a transformer and 20 having integral parts therein adapted to engage the ends and sides of the transformer to position it.
14. An electric gas igniter including an igniting element; a casing divided longitudinally to form two parts, each part having 25 a portion of a socket formed integrally therein; and a switch connected in a supply
- circuit for opening and closing said circuit, the switch being carried in and substantially enclosed by the said socket. 30
15. An electric gas igniter including an igniting element; a casing divided longitudinally to form two parts, each part having a portion of a socket formed integrally therein and provided with inwardly projecting ledges; a switch connected in a supply circuit for opening and closing said circuit and having a base plate supported on said ledges and contained within the socket. 35
16. In an electric gas igniter, a casing of 40 insulating material divided longitudinally to form two parts adapted to enclose and position a transformer, each part having transversely arranged bosses formed therein extending substantially to the line of division 45 of the casing; and bolts passing through the said bosses for securing the parts of the casing together; the said bosses being adapted to shield the bolts from contact with the said transformer. 50

Signed at Toronto, Canada, this 5th day of September, 1923.

JAMES H. RODEN.
